UNITED STATES PATENT OFFICE.

ROBERT D. GRAY, OF RIDGEWOOD, NEW JERSEY.

COMBINED PHONOGRAPH AND MOVING-PICTURE MACHINE.

Application filed June 5, 1920. Serial No. 386,899.

To all whom it may concern:

Be known that I, ROBERT D. GRAY, a citizen of the United States, residing at Ridgewood, in the county of Bergen, State of New Jersey, have invented certain new and useful Improvements in Combined Phonograph and Moving-Picture Machines; and I do hereby declare the following to be a full, clear, and exact description of the invention, 10 such as will enable others skilled in the art to which it appertains to make and use the same.

This invention relates to the recordation and reproduction of motion pictures simultaneously with sounds accompanying the action photographed.

The primary object of the invention is the provision of means whereby the photographic and sound record may be properly synchronized both in recordation and reproduction and of means for automatically starting the sound recorder or reproducer to ensure synchronization.

A further object of the invention is the provision of means for accelerating or retarding the visual record to permit adjustment when the synchronism of the records is disturbed.

Further objects and advantages of the invention will be apparent as it is better understood by reference to the following specification when read in connection with the accompanying drawing, in which

Fig. 1 is a diagrammatic view in elevation of the camera or projector and the sound recording or reproducing mechanism arranged and connected for synchronous actuation;

Fig. 2 is a sectional view of the film actuated device for controlling the starting of the sound record mechanism;

Fig. 3 is an elevation of the releasing device for the sound recorder;

Fig. 4 is a plan view partly in section;

Fig. 5 is an elevation of the releasing device for the sound reproducer;

Fig. 6 is an end elevation of the differential; and

Fig. 7 is a side elevation thereof.

In a copending application Serial No. 386,898 filed June 5, 1920, a method and means of simultaneously producing sound and photographic records is described, which permits a drama, for example, to be photographed while sounds accompanying the action are synchronously recorded. The

invention depends upon the distribution of concealed microphone transmitters about the stage or set in such relation that, at any required position, the voices of the actor or actors may be recorded, the sounds being conveyed electrically to a central recording station to which the transmitters are connected. Thus the recorded speech of the actors may be reproduced in proper relation to the accompanying movements or gestures and a very life-like representation of the drama is possible.

The present invention has to do more particularly with the mechanism employed for maintaining the synchronism of the photographic and sound records. While the preferred mode of applying the invention is illustrated, it is to be understood that the underlying principles thereof may be embodied in varying mechanical constructions which, within the scope of the accompanying claims, are a part of my invention.

Referring to Fig. 1 of the drawing, 5 indicates a suitable support for the camera or projector 6 and the sound recorder or reproducer 7, each of which may be of usual construction except as modifications hereinafter explained are introduced in carrying out the invention. Preferably the moving parts of the camera or projector and the recorder or reproducer are actuated by a motor 8 on the support 5 which drives the shaft 9. Suitable connections of usual form and construction are provided between the shaft 9 and the moving parts which need not be described in detail, since they are familiar to those skilled in the art.

To restore the normal synchronism of the separate mechanisms when disturbed, a differential 10 is provided in the shaft 9 and adapted to be manually actuated to accelerate or retard the visual record. Thus when parts of the film have been cut out, it is necessary to retard the feeding mechanism 100 therefor and if inserts have been made, acceleration is required to restore synchronism of the records.

To insure proper starting of the records, the film 11 is provided with a slot 12 which 105 may be formed therein when the film is prepared. A trip lever 13 is pivoted at 14 and is provided with a roller 15 adapted to enter the slot under the actuation of a spring 16, as a sprocket 17 intermittently advances 110 the film past a gate or aperture 18. When the trip lever is thus moved by the spring it

swings a contact device 19 into engagement with a post 20 and closes an electrical circuit through conductors 21 and 22. Thus a trip may be magnetically controlled to release the sound recording or reproducing mechanism as hereinafter described. The contact device 19 is normally held in inoperative position by a detent 23 which engages a notch 24 therein. A notch 25 is engaged 10 by the detent when the contact device is actuated as hereinbefore described to ensure proper contact and closure of the circuit. The contact device may be released and returned to inoperative position by means of 15 a projecting finger piece 26 and the same means may be employed to set the contact device in the position indicated in Fig. 2 of the drawing. The arrangement illustrated and described permits the use of a relatively 20 weak spring 16 so that injury to the film by the roller 15 is prevented.

If it is not convenient to slit the film before it passes through the camera, a marker 25 may be substituted for the roller 15 and the lever 13 may be manually tripped through the finger piece 26 projecting through the camera wall to mark the film simultaneously with the starting of the sound record. Positives, prepared from the negative thus 30 marked, may be slotted at a corresponding point to ensure synchronous starting of the records.

Separate devices are provided for starting recordation and reproduction of sound 35 both of which are controlled electrically by the circuit closure hereinbefore described. Such devices are essential in order that the mechanism may be permitted to attain its normal speed before recordation or reproduction commences. In Fig. 3 of the drawing, a record table 27 is mounted in the usual manner on a base 28 and is rotated through its connection with the motor 8. A recording stylus 29 is supported on a casing 30 which carries a diaphragm to which the stylus is connected. The casing 30 may be similar to the usual phonographic sound box and is preferably mounted on a support 31 which is fed across a record blank 32 by a 40 feed screw or other suitable means (not shown) such as is well known in the art. A tone arm 33 is connected to the sound box and is adapted to convey sounds from a translating device (not shown) in which 45 electrical pulsations from the transmitters above referred to are translated into sounds. Obviously the sounds may be delivered to the tone arm in any suitable manner.

The tone arm 33 carries a finger 34 which 50 normally rests on a cam 35 pivoted on the end of an arm 36, which is mounted on the base 28. The cam has a flat side 37 and carries an arm 38 of magnetic material which is held in spaced relation to an elec- 55 tro-magnet 39. The electro-magnet is con-

nected to the conductors 21 and 22 and to a source of current. Thus when the circuit is closed as the slot in the film passes the roller 15, the magnet is energized attracting the arm 38. The cam is thereby rotated and the finger 34 drops onto the flat side of the cam 35. The stylus 27 thus moves into engagement with the record blank, the support 31 being slotted to permit the tone arm to move vertically therein. 70 The record blank rotates in synchronism with the camera and the recording stylus is fed across the blank as the action proceeds thus recording the sounds in synchronism with the photographic record. When the 80 film is exhausted the apparatus is stopped and both the film and sound record are subjected to the usual processes in preparation for reproduction of the records.

In reproducing sound records it is necessary to provide a slightly different mechanism permitting the reproducing stylus to rest at the starting point on the stationary record while the actuating means acquires the necessary momentum. Referring to 90 Figs. 4 and 5 of the drawing, a frame 40 supports a post 41 having a flange 43. A rotatable table 44, mounted, for example, on balls 45, is supported on the frame 40 and is driven by engagement of a gear 46, on the shaft 9, with a circular rack 47. At the periphery of the table are a plurality of grippers 48 pivoted at 49 and connected by arms 50 to a central disc 51 having a handle 52. The grippers 48 are preferably provided with surfaces 52' of soft rubber or the like, and are adapted to grip the edges of a record 53 which is supported on the stationary flange 43. The disc 51 has a hub 54 loosely supported on the post 41, and connected by a spiral spring 55 to a yoke 56 beneath the table 44. When the disc 51 is turned to swing the grippers 48 away from the edge of the record, the spring 55 is tensioned and a notch 57 in the hub 54 engages 100 a lug 58 on a collar 59, which is mounted for vertical movement on the post 41 and prevented from rotating with respect to the yoke 56 by a pin 60. The collar 59 is held in its upper position by a spring 61 surrounding the post 41 and is engaged near its lower end by the jaws 62 of a non-rotatable armature 63. An electro-magnet 64 is connected to the conductors 21 and 22 and to a source of electrical energy. Thus when 110 the circuit is closed by the passage of the slot in the film past the roller 15 in the projector, the electro-magnet 64 is energized and the lug 58 is retracted. The spring 55 rotates the disc 51 and carries the grippers 48 into engagement with the sound record which is thereafter rotated with the table. The stylus 65 of the reproducer 7 being previously engaged in the record groove at the 120 starting point, the sound reproduction will 130

start synchronously with the photographic record.

It is a frequent practice to cut and splice film, sometimes removing portions and frequently inserting additional matter. Obviously the synchronism of the sound and photographic record is thus disturbed, and this may also result by accident. It is necessary, therefore, to provide means for restoring synchronism and a differential is illustrated in Figs. 5 and 6. This differential 10, referred to in the description of Fig. 1, comprises a frame 65' supported on the base 5 and furnishes a bearing for the shaft 9 carrying a gear 66 at its free end. A sleeve 67 is loosely supported on the shaft 9 and carries a gear 75 and a bevel pinion 67' which meshes with a corresponding gear 68 on a shaft 69, which drives the motion picture projector. A disc 70 is loosely mounted on the sleeve 67 and is normally held stationary by a pin 71 engaging a hole in a dial 76 on the frame 65'. A handle 72 is connected to the pin 71 and permits withdrawal thereof from the hole against the tension of a spring 73. The handle also permits manual rotation of the disc. Idle pinions 74 and 74' are rotatably supported on the disc 70 and mesh with gears 75 and 66 on the sleeve 67 and shaft 9 respectively. When the disc 70 is held stationary, the shaft 69 is driven from the shaft 9 through the gear train, sleeve 67 and bevel gear connections and at the same angular speed. If the synchronism of the mechanism is disturbed the disc 70 may be rotated in either direction to accelerate or retard the angular speed of the shaft 69 until synchronism is restored.

40 The adjusting handle 72 works with the dial 76 so as to conveniently indicate the extent to which the original relation of the machines has been adjusted. The dial may be marked in arbitrary divisions indicating a unit of film length, either inches or pictures, and by keeping account of the alterations in the length of the film as necessitated by revising the subject or cutting out torn and imperfect film, the extent of adjustment necessary to re-establish synchronism between the phonograph and the projector may be readily determined. For instance, if it is known that the film has been short-

ened five pictures at a certain point in the film, the operator will, when that point is 55 reached in the exhibition of the film, quickly move his handle from zero to 5, thereby being assured that the compensation has been exactly effected, instead of having to approximate the synchronizing by comparison 60 of the picture and the sound.

While the visual and sound reproducing mechanism is illustrated and described as directly coupled for simplicity, they may be separated and various means may be employed for driving them in synchronism. 65 This and other variations are within the spirit and scope of the invention as described and claimed herein.

In the appended claims I have used the 70 expression "sound record machine" in a generic sense to indicate either the sound recording machine or the reproducer.

I claim:

1. In an apparatus of the character described, the combination of a motion picture projector, a sound reproducer including a record and reproducing stylus, means for synchronously actuating the projector and reproducer and means controlled by the projector to initiate the reproduction including a stationary record support, rotating means for gripping the record, means for holding the gripping means in inoperative position and means for releasing the holding means. 75 80 85

2. In an apparatus of the class described, the combination of a motion picture machine, a sound record machine, means for actuating said machines in synchronism, means for altering the timed relation of the two 90 machines without permanently varying the speed relation, and means for indicating the extent to which the timed relation has been altered from the original setting, said means including a differential connected to 95 the actuating means and manually operable to accelerate or retard one of said machines, and a graduated stationary dial cooperating with the manually operable floating member of the differential to indicate the 100 change in position thereof from the original setting.

In testimony whereof I affix my signature.

ROBERT D. GRAY.
